UNITED STATES PATENT OFFICE

2,386,101

CONTAINER CARRIER

Theodore H. Firms and William E. Mackel, of Chicago, Ill.

Application March 10, 1944, Serial No. 525,932

7 Claims. (Cl. 294—87)

This invention relates to a device for carrying bottles or other containers, and its principal object is to provide a simple and inexpensive device, capable of carrying a number of containers at a time.

Another object is to provide a bottle carrier which may be readily placed upon the necks of a group of bottles, and by the simple act of lifting up on the handle of the device, it will be positively fastened upon the bottle necks, whereby the group of bottles may be safely carried about.

The invention further consists in a bottle carrying device, constructed of sheet material, struck up with suitable dies into finished form, easily assembled and serviceable for an indefinite period of time.

The invention further consists in the several novel features hereinafter fully set forth and claimed.

The invention is clearly illustrated in the drawing accompanying this specification, in which:

Fig. 1 is a side elevation of a bottle carrier embodying a simple form of the invention.

Fig. 2 is a plan thereof.

Fig. 3 is a vertical cross-section taken on the line 3—3 of Fig. 2, but showing the device fastened upon the bottles.

Fig. 4 is a vertical cross-section taken on the line 4—4 of Fig. 2.

Fig. 5 is a vertical longitudinal section taken on the line 5—5 of Fig. 2, and

Fig. 6 is a fragmental, vertical cross-section taken on the line 3—3 of Fig. 2, but showing the parts in carrying position.

Referring to said drawing, the reference characters 7, 8 designate two rectangular, generally flat plate-like members, movable transversely with respect to each other and guided and secured against disconnection from each other. Any suitable means may be provided for this purpose and as here shown, the plate member 8 is formed on its shorter edges with turned flanges 9a (see Fig. 5) which provide guide ways in which the shorter end edges of the plate member 7 are slidably carried.

The plate member 8 is provided with a down-turned flange 9 along three of its sides, and is further formed with a struck up bead 10 along said three sides, and the plate member 7 is also provided along three of its sides with a struck up bead 11, the parts 12 of which telescope into the parts 13 of the bead 10.

The plate members 7, 8 overlap each other as is clearly illustrated, and the edge portion 14 of

each plate member is formed with several approximately semi-circular notches 15, three being shown in each plate member. Each plate member is further formed with egg-shaped holes 16, the smaller arcs 17 of which are disposed opposite the semi-circular notches 15. The radii of the notches 15 and smaller round edges 17 of the holes 16 are approximately the same as the radii of the finish line of the standard soft drink bottles, some of which are shown at 18. These semi-circular edges of the plate members are adapted to engage with bottle necks at the finish line or, in other words, immediately below the conventional bead 19 of the bottles. The metal of the plate members at the semi-circular edge portions of the holes is struck downwards to provide flanges 20, which are adapted to grasp the bottle necks and prevent swaying of the bottles, that is to prevent them from knocking together.

The overall greatest dimension of the minor axes of the holes is approximately the same as or greater than the diameter of the beads 19 of standard bottles, whereby the device may be readily placed upon a group of bottles contained in a standard case of bottles. The device is illustrated for carrying six bottles, but this is entirely optional. It will be obvious from an inspection of Fig. 2 that when the device is placed upon the necks of six bottles, if the two plate members 15 are slid toward each other, the edges of the notches 15 and small radius edges 17 of the holes 16 will be impinged against the sides of the bottle necks below the beads 19.

Suitable means are provided for accomplishing this result, which means also comprise the handle of the device. As herein shown, a handle 21, provided with a wire bail, is employed, the legs 22 of which extend through slots 23 formed in the plate member 8 and through slots 24 formed on the plate member 7. The end extremities 25 of the legs are bent at right angles to the legs to lie in alignment with each other and are arranged to engage the underside of the plate member 7.

Aligned with slots 23, the metal of the plate member 8 is struck upwardly to provide two inverted U-shaped ribs 26, and the metal of the plate member 7 is struck up downwardly in alignment with the slots 24 to provide U-shaped ribs 27. The end edges 28, 29 of these U-shaped ribs provide fulcrum points against which the handle legs may be swung whenever the handle is raised, thereby sliding the plate members toward each other in a longitudinal direction and bringing the notches 15 and opposed semi-circular edge

portions 17 of the holes 16 toward each other and impinging them upon the necks of bottles upon which the carrier has been placed. The down-turned flanges 20 are brought to bear against the bottle necks, thereby serving to steady the bottles while being carried and thus prevent them from knocking together.

Fig. 4 shows the parts as they appear with the two plate members of the carrier slid apart and the legs of the handle extending obliquely through the slots and Fig. 6 shows a leg of the handle in upright position bearing against the edges 28, 29 of the U-shaped ribs. In this view the two plate members have been moved toward each other in a longitudinal direction with the bottle necks engaged by the edges of the notches 15 and semi-circular edges 17 of the holes 16 at the finish line of the bottles, and also with the flanges 20 engaging the bottle necks. The bottles may now be safely carried about.

To disengage the carrier from the bottles, the latter are stood upon a table or other horizontal surface, and the handle is permitted to drop, thereby releasing its purchase on the U-shaped ribs 26, 27, whereupon the two plate members may be drawn apart longitudinally far enough to bring the largest parts of the holes 16 into register with the bottle necks, after which the device may be readily raised therefrom.

From the above it is apparent that the carrier may be easily dropped over six bottles in a case or over a lesser number. The handle functions as a lever in closing the plate members upon the bottle necks. The plates are guided upon each other for longitudinal movement and are reinforced by ribs that telescope one into the other. Furthermore, the guides may be dispensed with, since the connection between the handle legs and plate members serves to guide the plate members. Obviously the carrier may be used for carrying containers other than bottles, that are provided with beads or shoulders at their upper ends.

We claim as new and desire to secure by Letters Patent:

1. A carrier comprising two plate members, slideable one upon the other, and formed with opposed container neck claspings elements, and a handle functioning as a lever and having two legs extending through aligned slots in the two plate members, there being ribs offset outwardly from said slots, and said legs of the handle being arranged when moved upward to engage opposed ends of the ribs and therewith move the plate members in opposite directions toward each other in the plane of the device.

2. A carrier comprising two plate members slideable one upon the other, one plate member having guide means for guiding the other plate member to slide parallel therewith, both said plate members having opposed container neck claspings elements, and both plate members having aligned slots extending transversely of the device, and a handle having legs extending through said slots, provided with shoulders on their extremities adapted to engage the underside of one plate member, the legs of the handle functioning as a lever engaging opposed ends of the slots, when the lever is raised, and thereby serving to move the neck claspings elements against the necks of the containers.

3. A carrier comprising two plate members slideably guided upon each other to move in the plane of the device, both plate members having opposed container neck claspings elements, and both plate members having aligned slots extending

transversely of the device, the upper plate member having inverted U-shaped ribs extending from one end of each slot and the lower plate member having U-shaped ribs extending from one end of each slot, with both sets of U-shaped ribs extending in opposite directions from each other, and a handle having legs extending through said slots and U-shaped ribs and being formed with extremities bent at right angles to the legs and arranged to engage the lower face of the lower plate, said handle legs functioning as levers acting against the opposed ends of the U-shaped ribs, whenever the handle is raised, whereby to slide the neck claspings elements of the plate members into claspings engagement with the container necks.

4. A carrier comprising two plate members slideably guided upon each other, both plate members having opposed flanged bottle neck claspings elements, and both plate members having aligned slots extending transversely of the device, the upper plate member having inverted U-shaped ribs extending from one end of each slot and the lower plate member having U-shaped ribs extending from one end of each slot, with both sets of U-shaped ribs extending in opposite directions from each other, and a handle having legs extending through said slots and U-shaped ribs and being formed with extremities bent at right angles to the legs and arranged to engage the lower face of the lower plate, said handle legs functioning as levers acting against the opposed ends of the U-shaped ribs, whenever the handle is raised, whereby to slide the neck claspings elements of the plate members into claspings engagement with the bottle necks.

5. A carrier comprising two plate members slideably guided upon each other, both plate members having a plurality of bottle neck receiving holes therein, and both plate members having notches in certain of their edges opposed to edges of said holes, said opposed notches and hole edges being adapted to be moved toward each other in claspings engagement with bottle necks, and both plate members having aligned slots extending transversely of the device, the upper plate member having inverted U-shaped ribs extending from one end of each slot and the lower plate member having U-shaped ribs extending from one end of each slot, with both sets of U-shaped ribs extending in opposite directions from each other, and a handle having legs extending through said slots and U-shaped ribs and being formed with extremities bent at right angles to the legs and arranged to engage the lower face of the lower plate, said handle legs functioning as levers acting against the opposed ends of the U-shaped ribs, whenever the handle is raised, whereby to slide the neck claspings elements of the plate members into claspings engagement with the bottle necks.

6. A carrier comprising two plate members slideably guided upon each other, both plate members having a plurality of flanged bottle neck receiving holes therein, and both plate members having flanged notches in certain of their edges opposed to edges of said holes, said opposed notches and hole edges being adapted to be moved toward each other in claspings engagement with bottle necks, and both plate members having aligned slots extending transversely of the device, the upper plate member having inverted U-shaped ribs extending from one end of each slot and the lower plate member having U-shaped ribs extending from one end of each slot, with

both sets of U-shaped ribs extending in opposite directions from each other, and a handle having legs extending through said slots and U-shaped ribs and being formed with extremities bent at right angles to the legs and arranged to engage the lower face of the lower plate, said handle legs functioning as levers acting against the opposed ends of the U-shaped ribs, whenever the handle is raised, whereby to slide the neck clasping elements of the plate members into clasping engagement with the bottle necks.

7. A bottle carrier comprising two plate members, one slidably guided upon the other, and both plate members having reinforcing ribs struck up

adjacent three sides of the plates, with the ribs on two edges aligned and telescoping each other, both plate members having opposed bottle neck clasping elements, and a handle having legs extending through aligned slots in both plate members and arranged to engage opposing ends of the slots when the handle is raised, whereby to move said plate members into bottle grasping position, said legs having their extremities bent to engage the lower face of the lower plate member.
